UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

COMBINED WIRE TIE AND TAG.

1,216,269.

Specification of Letters Patent. Patented Feb. 20, 1917.

Original application filed July 16, 1914, Serial No. 851,286. Divided and this application filed November 26, 1915. Serial No. 63,359.

To all whom it may concern:

Be it known that I, ADELMER M. BATES, a citizen of the United States, residing at Chicago, in the county of Cook and State 5 of Illinois, have invented a certain new and useful Improvement in Combined Wire Ties and Tags, of which the following is a specification.

This is a division of my application, Serial No. 851,286, filed July 16, 1914, for process of forming and tagging wire ties.

My invention relates to improvements in a combined wire tie and tag, and has for one object to provide a new and improved 15 form of tie for tying bags, packages and the like, wherein the tag is previously and permanently attached to the tie so that it does not require any particular attention from the operator, and so that the tag will 20 always be in position on the package whenever the package is tied. My invention is illustrated more or less diagrammatically in the accompanying drawings, wherein—

Figure 1 is a perspective view of a tie 25 with tag attached before the tie is put into use.

Fig. 2 is a perspective of a bag showing the tie and tag in the operative position.

Fig. 3 is a perspective of a modified form 30 of combined tie and tag.

Like parts are indicated by the same letter in all the figures.

A is the body of a wire tie having the loop ends B, B. C is the tag having a small 35 aperture D through which the body of the tie is inserted. The complete tie, of course, so arranged is, as it were, inseparable from the tag, for neither can be separated from the other. These will be made up in large 40 quantities for a given manufacturer and his employees have no additional labor to perform. They simply apply the wire tie in the usual form and the tag attached thereto and printed with the matter required will 45 thus be secured in place. The tie, which is delivered of course with the tag attached, is twisted around the neck of the bag or around a package or around any other objects which are to be held together. The

ends of the tie are twisted together in the 50 usual manner, and thus a tie and tag are both fastened to the object.

In the modified form it will be noted that the tag is localized at one position in the body of the tie. This is not the preferred 55 form, but under some circumstances it might be desirable to so position or localize the tag, and this arrangement might be used either with or without the enlarged ends. As indicated the tie is so made that 60 if it became necessary, the tag could be slipped out of the loop holding it, but still be held in position on the tie by enlarged or looped tie ends.

It will be noted that this application contains subject matter divided out of my 65 pending application Serial Number 851,286, filed July 16, 1914, and I wish that this application be regarded as a divisional application based thereupon.

The ends of the tie, which in this case take the form of the loop C, are as shown, larger than the perforation in the tag so that after the parts have been assembled, 70 the tag and tie cannot be separated without 75 destroying one or the other.

I claim:

1. The combination with a perforate tag body of a wire tie passing through said perforation, the ends of said tie being each 80 larger than said perforation, the tag being free to move along the tie limited only by its contact with the enlarged ends thereof.

2. The combination with a perforate tag body of a wire tie passing through said 85 perforation, closed loops formed on either end of said tie, said closed loops being larger than said perforation, the tag being free to move back and forth along the tie limited only by its contact with the loops. 90

In testimony whereof, I affix my signature, in the presence of two witnesses, this 23rd day of November, 1915.

ADELMER M. BATES.

Witnesses:

GRACE STAUNTON,
HEYDON WITTER.
